UNITED STATES PATENT OFFICE.

HAROLD S. LOOMIS, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA.

APPARATUS FOR CONTROLLING RAILWAY SWITCHES.

Application filed February 11, 1927. Serial No. 167,523.

My invention relates to apparatus for controlling railway switches, and particularly to apparatus suitable for operation from a distant point with a minimum number of 5 line wires between such point and the switch.

I will describe several forms of apparatus embodying my invention, and will then point out the novel features thereof in 10 claims.

In the accompanying drawings, Fig. 1 is a diagrammatic view showing one form of apparatus embodying my invention. Figs. 2, 3, 4 and 5 are diagrammatic views showing several modifications of a portion of the apparatus illustrated in Fig. 1 and also embodying my invention.

Similar reference characters refer to similar parts in each of the several views.

Referring first to Fig. 1, the reference characters 1 and 1^a designate the rails of a stretch of railway track which is provided with a switch 2 of the usual and well known form. This switch is operated by a fluid pressure motor A comprising a cylinder 3 containing a reciprocable piston 4. Attached to the piston 4 is a plunger 5 which is operatively connected with the movable points of the switch 2 through suitable mechanism 30 which is indicated by the dotted line 5^a.

The motor A is controlled by a switch valve C. This valve comprises a slide valve 7 operating in a valve chamber 6 which, in the form here shown, is constantly supplied with fluid pressure from a source not shown in the drawing through pipe 11. When the slide valve is in its normal position, in which it is illustrated in the drawing, fluid pressure is supplied from chamber 6, through pipe 10 to the lower end of cylinder 3 of motor A, and the upper end of this cylinder is connected with atmosphere through pipe 8 and port 9. With the valve in this position, therefore, piston 4 is moved upwardly and the switch then occupies what I shall hereinafter term its "normal" position. When the slide valve 7 occupies its reverse position, pipe 8 is connected with chamber 6 and pipe 10 is connected through port 9 to atmosphere. The piston 4 is then driven downward and the switch 2 is moved to its "reverse" position.

Valve 7 is provided with two spaced

notches 15 and 16 arranged to receive a locking rod 17 when the valve is in the reverse or normal position, respectively. Rod 17 is constantly urged toward the slide valve 7 by a spring 20, and it carries an armature 18 associated with a lock magnet 19. When the lock magnet 19 is energized, armature 18 is moved outwardly, thereby withdrawing the rod 17 from the notch 15 or 16 in the slide valve and permitting the valve to be shifted by means which I will describe hereinafter. It will be plain, however, that the valve can be shifted only when the lock magnet 19 is energized to lift the rod 17 clear of the valve.

The switch valve C also comprises two oppositely disposed axially aligned cylinders 12 and 12^a. Cylinder 12 contains a piston 13 carrying a stem 14 which engages one end of the slide valve 7, and the cylinder 12^a contains a piston 13^a carrying a stem 14^a which engages the other end of the slide valve. Cylinder 12 is at times supplied with fluid pressure by a valve 21 comprising a valve stem 23 controlled by a "reverse" magnet 25 having an armature 24 associated therewith. When reverse magnet 25 is de-energized the valve stem 23 occupies its left-hand position and cylinder 12 is connected with atmosphere. When reverse magnet 25 of valve 21 is energized, however, the valve stem 23 is moved to the right and cylinder 12 is disconnected from atmosphere and is connected with a source of fluid pressure. In similar manner, the valve 22 controls the supply of fluid pressure to cylinder 12^a in such manner that when the "normal" magnet 25^a of valve 22 is de-energized, cylinder 12^a is connected with atmosphere, but that when this magnet is energized cylinder 12^a is supplied with fluid pressure. It will be plain from the drawing that when cylinder 12^a is supplied with fluid pressure, piston 13^a is moved upwardly to drive valve 7 to its normal position. When cylinder 12 is supplied with fluid pressure however, piston 13 moves downward and drives the valve 7 to its reverse position. In either case, of course, movement of valve 7 is possible only if the lock magnet 19 is energized.

The normal magnet 25, the reverse magnet 25^a and the lock magnet 19 are controlled by a manually operable switch lever desig-

nated in general by the reference character L. This lever may be located at a point distant from the switch and may, for example, be one of a plurality of such levers located 5 in an interlocking machine in an interlocking cabin. The switch lever L has the usual normal and reverse positions, corresponding to the normal and reverse positions of the switch, and as shown in the drawing the 10 lever is in its normal position.

The normal magnet 25^a is provided with a circuit which may be traced from the upper terminal of a suitable source of energy such as a battery B, through wire 32, normal 15 contact 33 of lever L, wire 34, conductor 35, wires 36 and 37, asymmetric unit 28, wire 38, normal magnet 25^a, wire 39 and conductor 40, back to the mid-point 27 of the battery B. The circuit for the reverse magnet 20 25 may be traced from the mid-point 27 of battery B, through conductor 40, wires 41, 42 and 43, reverse magnet 25, wire 44, asymmetric unit 29, conductor 35, and wire 50, reverse contact 51 of lever L, and wire 52 back 25 to the lower terminal of battery B. The lock magnet 19 is provided with one circuit which may be traced from the upper terminal of battery B, through wire 32, normal 30 contact 33 of lever L, wire 34, conductor 35, wires 36 and 37, asymmetric unit 28, wires 38 and 53, contact K², wires 54 and 48, lock magnet 19, wire 47, asymmetric unit 30, wires 75, 41, and conductor 40, back to the mid-point 27 of battery B. The lock magnet 19 35 is provided with another circuit over which current at times flows from the mid-point 27 of battery B through conductor 40, wires 41 and 42, contact K¹, wires 46 and 47, lock magnet 19, wires 48 and 49, asymmetric unit 40 31, wire 36, conductor 35, and wire 50, reverse contact 51 of lever L and wire 52 back to the lower terminal of battery B.

The contacts K¹ and K² are operatively connected with the movable points of switch 45 2 and are controlled in such manner that contact K¹ is open when the switch occupies its extreme reverse position but is closed at all other times, and contact K² is open when the switch occupies its extreme normal position, but is closed at all other times.

The operation of the apparatus is as follows: As shown in the drawing, the lever L occupies its normal position so that current is supplied to the normal magnet 25^a through 55 the asymmetric unit 28, but the asymmetric unit 29 prevents the supply of current to the reverse magnet 25. One circuit for the lock magnet 19 is open at contact K², and the asymmetric unit 31 prevents the flow of current through this magnet over the remaining circuit. It follows that the normal magnet 25^a is energized but that the reverse magnet 25 and the lock magnet 19 are de-energized. 60 The slide valve 7 therefore occupies its normal position and is locked in this position 65

by the locking rod 17. Under these conditions fluid pressure is supplied to the lower end of cylinder 3, and piston 4 occupies its upper position so that the switch 2 is normal. If, now, the operator in charge of lever L 70 wishes to reverse the switch 2, he moves the lever L to its reverse position. Current therefore flows to reverse magnet 25 through the asymmetric unit 29, but the asymmetric unit 28 prevents the flow of current to the 75 normal magnet 25. Contact K¹ is closed and current therefore flows to the lock magnet 19 over contact K¹ and asymmetric unit 30, thereby disengaging the locking rod 17 from the slide valve 7. With the reverse 80 magnet 25 energized, fluid pressure is supplied to cylinder 12 and the slide valve 7 is shifted to the reverse position. Fluid pressure is then supplied to the upper end of cylinder 3 and the switch 3 is moved to its 85 reverse position. When the switch is fully reversed, contact K¹ opens, thereby de-energizing the lock magnet 19 and permitting the spring 20 to move the locking rod 17 into the notch 15 to hold the slide valve 90 in the position which it then occupies.

In similar manner, if the operator wishes to restore the switch to its normal position he returns the lever L to its normal position in which it is illustrated in the drawing. 95 Current then again flows to the normal magnet 25^a and the reverse magnet 25 becomes de-energized. The contact K² is closed, however so that current flows to the lock magnet 19 through contact K² and asymmetric units 100 28 and 30. The locking rod 17 is therefore withdrawn from engagement with the slide valve 7 and the slide valve is shifted to its normal position, thereby supplying fluid pressure to the lower end of cylinder 3 and moving piston 4 upwardly to restore the switch to its normal position. When the switch reaches its extreme normal position, contact K² opens, thereby interrupting the 105 circuit for lock magnet 19 and causing this magnet to become de-energized.

Each of the asymmetric units 28, 29, 30 and 31 may for example be of the type disclosed and claimed in an application for Letters Patent of the United States, Serial No. 1111, filed Jan. 7, 1925, by Lars O. Grondahl, for Unidirectional current carrying devices, and which has matured into Patent Number 1,640,335, dated August 23, 1927, although I do not wish to be limited to any specific type of unit.

It will be plain that by the use of the asymmetric units in conjunction with the contacts K¹ and K², the normal, reverse and lock magnets of the usual switch valve may be controlled from a distant point in accordance with my invention over a single pair of conductors 35 and 40 without sacrificing any of the usual elements of safety.

Another arrangement or circuits for con-

trolling the magnets of the switch valve C is illustrated in Fig. 2. In this view as well as in Figs. 3, 4 and 5, the various parts which are controlled by the magnets 25, 25^a and 19 are omitted for the sake of simplicity, only the magnets themselves and their controlling circuits being illustrated in the drawing. In Fig. 2 when the lever L is in its normal position, current from battery B flows over normal contact 33 of the lever, conductor 35, wires 61 and 62, asymmetric unit 28, normal magnet 25^a, wires 63, 64 and 65, asymmetric unit 55, wires 66, 67, 68, conductor 40, normal contact 51 of lever L and back to battery B. If the switch is in its reverse position when this circuit is closed so that contact K² is also closed, current flows from battery B, over normal contact 33 of lever L, conductor 35 and wire 61, asymmetric unit 59, contact K², wire 72, lock magnet 19, wire 73, asymmetric unit 60, conductor 40, and normal contact 51 of lever L, back to battery B. Under these conditions the lock magnet is energized and the normal magnet 25^a is also energized so that the switch is shifted to its normal position. When the switch completes its stroke, contact K² opens and the lock magnet 19 then becomes de-energized. If now the lever L is moved to its reverse position, current from battery B flows over the reverse contact 33 of the lever, conductor 40, wires 68 and 67, asymmetric unit 29, reverse magnet 25, wires 69, 64 and 70, asymmetric unit 56, wires 71, 62, 61, conductor 35, wire 76, reverse contact 51 of lever L and back to battery B. The reverse magnet 25 is therefore energized and the lock magnet 19 is also energized but the normal magnet 25^a is de-energized because asymmetric units 28 and 55 prevent the flow of current to this magnet. The slide valve 7 is therefore moved to its reverse position and the switch 2 is shifted to its reverse position whereupon contact K¹ opens and de-energizes the lock magnet 19. The operation of the apparatus when switch lever L is restored to its normal position will be manifest from the foregoing, without further explanation.

In Fig. 3 the circuits for the normal and reverse magnets 25^a and 25 are similar to the circuits for these parts shown in Fig. 2, but the locking magnet 19 is provided with two circuits, one of which passes from conductor 35, through asymmetric unit 59, locking magnet 19 and contact K² back to conductor 40 and the other circuit may be traced from conductor 40, through asymmetric unit 57, locking magnet 19 and contact K¹ to conductor 35.

In the modification illustrated in Fig. 4 the normal and reverse magnets 25^a and 25 are connected in parallel across the conductors 35 and 40. The asymmetric unit 28 is interposed between conductor 35 and mag-

net 25^a and the oppositely disposed asymmetric unit 29 is interposed between the conductor 35 and reverse magnet 25. The normal magnet 25^a is therefore energized when the switch lever occupies its normal position and the reverse magnet 25 is energized when the switch lever occupies its reverse position. In the form here shown the lock magnet is provided with two windings 19^a and 19^b. When contact K² is closed, winding 19^b of the lock magnet is connected in parallel with the normal magnet 25^a and when contact K¹ is closed, the winding 19^a of the lock magnet is connected in parallel with the reverse magnet 25. The apparatus is so arranged that when energy is supplied to either of the windings 19^a or 19^b of the lock magnet over one of the circuits just described, the locking rod 17 is withdrawn from the notches in the slide valve to permit the valve to be shifted.

In the modification shown in Fig. 5 the normal and reverse magnets 25^a and 25 are connected in parallel across the conductors 35 and 40 through asymmetric units 28 and 29, respectively, in the manner described in connection with Fig. 4. The apparatus shown in this view differs from that of Fig. 4, however, in that the locking magnet 19 is a single winding which is connected across the conductors 35 and 40 through an asymmetric unit 59 when contact K² is closed and is connected across these conductors through an oppositely disposed asymmetric unit 57 when contact K¹ is closed.

The operation of the apparatus shown in Figs. 3, 4 and 5 is similar to the operation of the apparatus shown in the two preceding views and will be readily understood without tracing the cycle of operation in detail.

Although I have herein shown and described only a few forms of apparatus embodying my invention, it is understood that various changes and modifications may be made therein within the scope of the appended claims without departing from the spirit and scope of my invention.

Having thus described my invention what I claim is:

1. In combination, a switch valve comprising a normal, a reverse and a lock magnet, a railway switch controlled by said valve, a switch lever having normal and reverse positions, a circuit for the normal magnet including a normal contact of the switch lever and a first asymmetric unit, a circuit for the reverse magnet including a reverse contact of the switch lever and a second asymmetric unit, contacts operated by said switch, and circuits for said lock magnet controlled by said switch lever contacts and by said switch operated contacts and including asymmetric units.
2. In combination, a switch valve comprising a normal, a reverse and a lock magnet controlled by said switch lever contacts and by said switch operated contacts and including asymmetric units.

2. In combination, a switch valve comprising a normal, a reverse and a lock magnet controlled by said switch lever contacts and by said switch operated contacts and including asymmetric units.

magnet, a railway switch controlled by said valve, a switch lever having normal and reverse positions, a circuit for the normal magnet including a normal contact of the switch lever and a first asymmetric unit, a circuit for the reverse magnet including a reverse contact of the switch lever and a second asymmetric unit, two contacts operated by the switch, and two circuits for the lock magnet controlled by the switch lever and each including one of said contacts and an asymmetric unit.

3. In combination, a switch valve comprising a normal, a reverse and a lock magnet, a railway switch controlled by said valve, a switch lever having normal and reverse positions, a circuit for the normal magnet including a normal contact of the switch lever and a first asymmetric unit, a circuit for the reverse magnet including a reverse contact of the switch lever and a second asymmetric unit, two contacts responsive to the position of the switch, means effective when one of such circuits is closed and when one of said contacts is closed to supply energy to the lock magnet, and means effective when the other circuit is closed and when the other contact is closed to supply current to the lock magnet.

30 4. In combination, a switch valve comprising a normal, a reverse and a lock magnet, a railway switch controlled by said valve, a switch lever having normal and reverse positions, a circuit for the normal magnet including a normal contact of the switch lever and a first asymmetric unit, a circuit for the reverse magnet including a reverse contact of the switch lever and a second asymmetric unit, two contacts controlled in accordance with the position of the switch, and means including said two contacts for supplying current to the lock magnet in parallel with the normal or reverse magnet depending upon the position of the lever.

5. In combination, a pair of conductors, means for reversibly supplying current to the conductors; a switch valve comprising a normal magnet, a reverse magnet, and a lock magnet having two windings; means including two oppositely disposed asymmetric units for connecting the normal and reverse magnets in parallel across the conductors, a railway switch controlled by the switch valve, and two contacts controlled in accordance with the position of the switch and connected in series with the windings respectively of the lock magnet across said conductors.

60 6. In combination, a pair of conductors, means for reversibly supplying current to the conductors; a switch valve comprising a normal magnet and a reverse magnet connected in parallel across the conductors and a lock magnet having two windings, a first

asymmetric unit interposed between the normal magnet and one conductor, a second asymmetric unit interposed between the reverse magnet and one of the conductors, a railway switch controlled by the switch valve, two contacts controlled in accordance with the position of the switch, means including one of said contacts for connecting one winding of the lock magnet in parallel with the normal magnet, and means including the remaining contact for connecting the other winding of the lock magnet in parallel with the reverse magnet.

7. In combination, a railway switch having normal and reverse positions, means for operating the switch including a normal and a reverse magnet, a pair of conductors connected with both said magnets, a source of current, a manually operable lever for reversibly connecting the source with the conductors, a first asymmetric unit interposed between the normal magnet and a conductor for preventing the flow of current of one polarity through the normal magnet, and a second asymmetric unit interposed between the reverse magnet and a conductor for preventing the flow of current of the opposite polarity through the reverse magnet.

8. In combination, a switch valve comprising a normal, a reverse, and a lock magnet, a railway switch controlled by the switch valve, a pair of conductors connected with the normal and the reverse magnets, manually controlled means for reversibly supplying current to the conductors, a first asymmetric unit interposed between the normal magnet and a conductor for preventing the flow of current of one polarity through the normal magnet, and a second asymmetric unit interposed between the reverse magnet and a conductor for preventing the flow of current of the opposite polarity through the reverse magnet, a contact controlled by the switch, and means controlled by the contact for at times connecting the lock magnet with the conductors.

9. In combination, a switch valve comprising a normal, a reverse, and a lock magnet, a railway switch controlled by the switch valve, a pair of conductors connected with the normal and the reverse magnets, manually controlled means for reversibly supplying current to the conductors, a first asymmetric unit interposed between the normal magnet and a conductor for preventing the flow of current of one polarity through the normal magnet, and a second asymmetric unit interposed between the reverse magnet and a conductor for preventing the flow of current of the opposite polarity through the reverse magnet, two contacts controlled by the switch and means controlled by each contact for at times connecting the lock magnet with the conductors.

10. In combination, with a railway switch, two windings for controlling the switch, two contacts controlled by the switch, two asymmetric units, means including one of said contacts and one of said units for supplying current to one winding, and means including the other contact and the other unit for supplying current to the other winding.
11. In combination, a railway switch having a normal and a reverse position, a first contact open only when the switch is normal, a second contact open only when the switch is reverse, two asymmetric units, two windings for controlling the switch, a circuit for one winding including the first contact and one of said asymmetric units, and a circuit for the other magnet including the remaining asymmetric unit and the second contact.
12. In combination, a pair of conductors, means for reversibly supplying current to such conductors, a railway switch having a normal and a reverse position, a first contact open only when the switch is normal, a second contact open only when the switch is reversed, two windings for controlling the switch, two asymmetric units, means including one of such units and said first contact for at times supplying current of one polarity from the conductors to one of the windings, and means including the other asymmetric unit and the second contact for at times supplying current of the other polarity from the conductors to the remaining winding.
13. In combination, a railway switch, contacts controlled in accordance with the position of the switch, a manually operable lever, two windings for controlling the switch, and means including asymmetric units for controlling the windings selectively in accordance with the condition of said lever and of said contacts.
14. In combination, a pair of conductors, means for reversibly supplying current to such conductors, a railway switch, two magnets for controlling the switch, a first asymmetric unit for connecting one magnet across the conductors, and a second asymmetric unit for connecting the other magnet across the conductors.
15. In combination, a motor, means including a magnet for controlling the supply of energy to said motor, two contacts responsive to the condition of said motor, and means including asymmetric units for controlling the magnet by a selected one of such contacts.
16. In combination, a pair of conductors, means for reversibly supplying current to the conductors; a switch valve comprising a normal magnet; a reverse magnet, and a lock magnet having two windings; a railway switch controlled by said switch valve, means for connecting one terminal of each said winding and one terminal of the normal and reverse magnets with one of said conductors, means including a first asymmetric unit for connecting the free terminal of the normal magnet with the other conductor, means including a second asymmetric unit for connecting the free terminal of the reverse magnet with said other conductor, and two contacts controlled in accordance with the position of the switch for separately connecting the free terminals of the windings of the lock magnet with said free terminals of the normal and reverse magnets respectively.

In testimony whereof I affix my signature.

HAROLD S. LOOMIS.
